DESIGN FOR A JAR

Frasier Smith, Wheeling, W. Va., assignor to
Hazel-Atlas Glass Company, Wheeling, W. Va.,
a corporation of West Virginia

Application June 8, 1940, Serial No. 92,902

Term of patent 14 years

To all whom it may concern:

Be it known that I, Frasier Smith, a citizen of the United States, residing at Wheeling, in the county of Ohio, and State of West Virginia, have invented a new, original, and ornamental Design for a Jar, of which the following is a specification, reference being had to the accompanying drawing, forming part thereof.

Figure 1 is a perspective view of the jar showing my new design, and

Figure 2 is a horizontal sectional view taken on line 2—2 of Figure 1.

I claim:

The ornamental design for a jar, as shown.

FRASIER SMITH.
